DESIGN FOR A PICTURE BIRTHDAY MEMO BOOK

Annette T. Turpin, Los Angeles, Calif.

Application July 19, 1947, Serial No. 140,520

Term of patent 14 years

(Cl. D6—2)

To all whom it may concern:

Be it known that I, Annette T. Turpin, a citizen of the United States, residing at Los Angeles, in the county of Los Angeles and State of California, have invented a new, original, and ornamental Design for Picture Birthday Memo Book, of which the following is a specification, reference being had to the accompanying drawing, forming part thereof.

The figure is a perspective view of a picture birthday memo book in an open position, showing my new design, the black cover being plain on the outside.

I claim:

The ornamental design for a picture birthday memo book, as shown and described.

ANNETTE T. TURPIN.
